(57) **CLAIM**

The ornamental design for a circuit interrupter, as shown and described.

DESCRIPTION

FIG. 1 is an upper left perspective view of a first embodiment of the circuit interrupter;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is an upper left perspective view of a second embodiment of the circuit interrupter;

FIG. 9 is a front elevational view thereof;

FIG. 10 is a right side elevational view thereof;

FIG. 11 is a left side elevational view thereof;

FIG. 12 is a top plan view thereof;

FIG. 13 is a bottom plan view thereof; and,

FIG. 14 is a rear elevational view thereof.

In the drawings, the broken lines are for the purpose of illustrating environment only and form no part of the claimed design.

1 Claim, 12 Drawing Sheets
